ATTORNEY.

UNITED STATES PATENT OFFICE.

GEORGE W. JOHNSON, OF LATROBE, PENNSYLVANIA.

ELECTRIC PRINTING-MACHINE.

1,351,655.

Specification of Letters Patent. Patented Aug. 31, 1920.

Application filed January 28, 1919. Serial No. 273,529.

To all whom it may concern:

Be it known that I, GEORGE W. JOHNSON, a citizen of the United States, residing at Latrobe, in the county of Westmoreland 5 and State of Pennsylvania, have invented certain new and useful Improvements in Electric Printing-Machines, of which the following is a specification.

This invention relates to photography, 10 and more especially to printing, and the object of the invention is to produce a machine which may be used for the printing of photographs from negatives by means of electricity.

One feature of the invention lies in the 15 automatic means for cutting off the current to the strong electric bulb when the machine is opened.

Another feature lies in the use of a weak 20 or ruby bulb burning constantly and which may be serviceable for lighting the dark room.

A detail of the invention consists in the 25 automatic means for closing the switch to the strong light when the door of the machine is closed.

Details are set forth below, and attention 30 is drawn to the drawings, wherein—

Figure 1 is a perspective view of this machine open.

Fig. 2 is an enlarged vertical section of the machine with the door closed.

Fig. 3 is a diagram showing the wiring.

The numeral 1 designates a box-like casing having at its top a cover 2 hinged at its rear at 3 and adapted when closed down to be fastened in place by means of a hook and eye connection, 4, 5 at each side. The front upper corner of the box is beveled off as at 35 6 and the base 7 projects forward and affords a table 8. The beveled panel 6 is provided with an opening 16 surrounded on its interior by a flange 17 on which lies a pane of glass 18. Connected with the panel 6 at 40 45 one end of the opening by any suitable means as by hinges (not shown), is a two-part door 19 whereof the parts are hinged to each other and lined on their inner faces with fabric so as to closely overlie the sensitive paper and film when the same are laid 50 upon the glass. At the free edge the door carries a tongue 11 adapted to fall into a recess or notch 12 in the panel 6, and the tip of the tongue is connected with the body of 55 the casing by hook and eye elements 14, 15 as shown. The position of these elements is

such that when they are engaged the tongue is drawn tight down into the recess or notch 12 and the door tight into the opening 16, upon the glass, with the paper and film 60 intervening.

Carried by the panel 6 at an appropriate point, and herein shown as above the opening 16, is a weak light and preferably an incandescent bulb having a red or ruby 65 globe as indicated at R. Mounted upon a suitable support 20 within the box-like casing 1, is a strong light, preferably a white incandescent bulb indicated at W. A two-wire cable 21 leads into the casing, either 70 through the opening beneath its cover or any appropriate point, and the wires are then diverted and one of them led through a knife switch 22 as shown, the wiring being perhaps best illustrated in Fig. 3. To 75 the free end of the blade of the switch is connected a rod 23 having a head 24 normally raised by a spring 25, and above this head is a plunger 26 whose head 27 in turn rises into the notch and recess 12. When 80 now the tongue is brought over into said recess it bears on the head 27 and depresses the plunger, and the plunger in turn bears on the head 24 and depresses the rod. This in turn depresses the free end of the switch 85 blade, so that a circuit is closed to the large white lamp W, and the same is illuminated at a time when the sensitive paper and film has been tightly clamped down upon the glass 18 within the periphery of the opening 16. The obvious purpose of having the door 19 in two parts is to permit the operator to unlatch the outer leaf or part and swing it back, while holding the inner leaf or part and the film and paper, and turn 90 up the paper to ascertain to what extent the printing has been carried. This is well known to photographers. Obviously he may restore the parts to their position, and pressure on the tongue before it can be 100 hooked in place cuts on the current and the bulb W is immediately lighted. So long as the current flows from the source of electricity, the ruby globe R is lighted and affords light to the whole interior of the 105 dark room within which this machine is located, and it also gives direct light upon the film and the picture being printed, when the door is turned back wholly or in part. Unless the operator shall deliberately press 110 upon the head 27 of the plunger 26, it is impossible to close the switch 22, and there-

fore the bulb W will not be illuminated until the door 19 is closed. This of course will not occur until the film and paper have been placed in position and the cover closed 5 and hooked. It is possible that the cable 21 may have a plug at its remote end (not shown) to be connected to any ordinary socket in the house system, and when this device is not in use the cable and its plug 10 may be placed within the casing and the cover closed and hooked.

The foregoing description and the drawings have reference to what may be considered the preferred or approved form of 15 my invention. It is to be understood that I may make such changes in construction and arrangement and combination of parts, materials, dimensions, et cetera, as may prove expedient and fall within the scope of the 20 appended claim.

Having thus fully described my invention, what I claim as new and desire to secure by Letters Patent is:-

In a device of the character described, the 25 combination of a casing including a circuit therein having a lamp and a knife switch, a rod connected to said knife switch and having a head on its outer end, a coiled

spring surrounding said rod and engaging said head for forcing the same in one direction to hold the switch normally open, an abutment means on said casing for said spring, said head adapted to compress said coil spring against said abutment, said casing having a print receiving portion provided with a sectional door, said casing having a recess contiguous to the receiving portion, a plunger extending into said recess and having its inner end contacting with the head of said rod, a tongue extending 40 from one section of the door and adapted to be received within the recess as the door is closed to strike said plunger and cause the same to depress said rod to close the switch, although when one section of the 45 door is opened for the usual purposes the tongue will be removed from the plunger to cause the spring to again open the switch, as and for the purposes set forth.

In testimony whereof I affix my signature 50 in presence of two witnesses.

GEORGE W. JOHNSON.
